EDWARD L. DUNN, OF WORCESTER, MASSACHUSETTS, ASSIGNOR TO STANDARD PLUNGER ELEVATOR COMPANY, OF NEW YORK, N. Y., A CORPORATION OF NEW JERSEY.

PUMPING SYSTEM.

1,037,879.

Specification of Letters Patent. Patented Sept. 10, 1912.

Application filed September 3, 1909. Serial No. 516,100.

To all whom it may concern:

Be it known that I, EDWARD L. DUNN, a citizen of the United States, residing at Worcester, in the county of Worcester and State of Massachusetts, have invented certain new and useful Improvements in Pumping Systems, of which the following is a full, clear, and exact specification.

This invention relates to automatic pumping systems, and more particularly has reference to pressure pumping systems wherein it is desired to automatically maintain a supply of hydraulic fluid in a tank under an approximately constant pressure as for use in operating elevators, presses and other machinery.

In such systems as now commonly employed an electrically driven pump is used for pumping the water into the storage tank, and this pump and its motor are automatically started and stopped as the pressure in the tank falls or rises. In such a system it will be seen that the motor must be started and stopped a great number of times where the machinery operated by the system is in frequent use, sometimes as frequently as once every minute. Where there is a large pump it is a difficult matter to automatically start and stop it so frequently, and furthermore the starting load on a pump is very great by reason of the inertia of the column of water which has to be moved, thereby requiring excessive starting current for the motor. Consequently, there is an excessive strain and wear and tear on the apparatus, requiring frequent attention and considerable removal.

According to this invention, I propose to provide a pumping system wherein a predetermined pressure will be automatically maintained in the pressure tank by a continuously running motor and pump, combined with automatic valve controlling mechanism whereby as long as there is a predetermined pressure in the tank the pump simply circulates the water through the discharge tank, but when the pressure in the storage tank falls, the valve mechanism automatically operates to connect the discharge side of the pump to the tank to

restore the pressure, whereupon the automatic valve is again shifted to connect the discharge side of the pump to the discharge tank. Thereby there is an ultimate saving in current and also excessive strain and wear and tear on the machinery avoided.

In the specific embodiment of the invention herein shown, the discharge of the pump is controlled by a pressure operated direction valve, and the pressure to this direction valve is automatically governed by a solenoid operated pilot valve and a pressure actuated switch system controlled by the storage tank pressure which controls the pilot valve solenoid.

The invention will be more fully understood in connection with the description of the accompanying drawing, wherein 1 represents a pump, and 2 a motor belted thereto through pulley 3. 4 a pressure tank having an inlet pipe 5, 6 the discharge tank into which the exhaust from the machinery will be discharged through a pipe 7, and 8 is the supply pipe from the pressure tank 4 to the machinery. The machinery and the controlling valves are not herein shown, not being necessary to a full understanding of this invention.

9 is the pump intake pipe leading from the lower portion of tank 6 to the pump 1, and 10 is the pump discharge leading to the direction valve 11. The direction valve comprises a stem 12 having at each end operating pistons 13, 14 and a controlling piston 15. Also connected to the direction valve 11 is a discharge pipe 16 discharging into the tank 6. In the position shown, it will be seen that the pump is taking water from the tank 6 through the pipe 9 and discharging it through the pipes 10 and 16 into the discharge tank, while the pressure from tank 4 exerted through pipe 5 is balanced between pistons 13 and 15 without moving the valve stem 12. When the piston 15 is below the pipe 10, it will be seen that the pump will then be pumping through pipes 10 and 5 directly into the pressure tank 4.

In order to automatically operate the direction valve, I have provided a pilot valve mechanism 18 having to-and-fro pipe 19 connected to the direction valve 11 above

the piston 13, and a to-and-fro pipe 20 connected below the piston 14. The pilot valve 18 comprises a stem 22 carrying pistons 23, 24, 25, 26, and also supply pipe 27 having a branch 28, an exhaust pipe 29 having a branch 30. In the position shown, the pilot valve is at its lowest position, and it will be seen that pressure above piston 26 will be admitted through pipe 28 and thence through pipe 20 to the lower side of direction valve piston 14. At the same time, the pipe 19 and thereby the space above direction valve piston 13 is open to the exhaust through pipe 19 and between piston 23 and 24 to exhaust pipe 29, thus holding the direction valve positively in the position shown by the pressure. This pressure may be derived from a suitable source not necessary to be shown herein. When the pilot valve stem is at its upper position, it will be seen that piston 23 cuts off the exhaust pipe 29, while piston 24 moves to such position as to connect pipes 27 and 19, thus admitting pressure above the direction valve piston 13. At the same time, the piston 14 will be open to the exhaust through pipe 20 and below piston 26 to pipe 30 and thence to pipe 29, the latter being the exhaust pipe. It will be seen that there is always unbalanced pressure through pipe 28 on the pilot valve piston 26, so that the pilot valve always tends normally to move downward under this pressure. In order to lift the pilot valve, the solenoid 33 is employed having its core 34 connected to the pilot valve stem 22, and this solenoid is automatically controlled by a pressure actuated switch 35 which I will now describe.

In the position shown, the pressure actuated switch 35 has just been moved by the fall of pressure in the tank 4 to cause the direction valve 11 to connect the pump with the tank. 36 is the main line switch, also controlling the motor, and from one contact on this switch a wire 37 leads through solenoid 33 and thence by wire 38 to movable contact 39. 40 is a stationary contact leading through solenoid 41 and thence the circuit branches, one branch 42 leading to the pressure operated switch 35, and the other branch 43 leading to a stationary contact 44.

45 is a movable contact operated simultaneously with contact 39 by energization of solenoid 41 connected to the return side of the line by wire 46 leading through a holding resistance 47. Also leading to the main switch is a wire 48 leading through a resistance 49, and thence through solenoid 41. Branching from the connection between the resistance 49 and the solenoid 41 is a wire 50 leading to contact 51 of the pressure switch 35. Also there is a contact 52 connected by wire 53 to the return side of the line.

In the position shown, it will be seen that

the pump is running idly while the switch 65 blade 35 has just moved in response to fall in pressure in the tank 4 so as to make contact at 52. Upon this being done, the circuit on solenoid 41 is made through wires 48, resistance 49, wire 42, blade 35, contact 70 52, wire 53 to return side of line, thus energizing solenoid 41 and closing the contacts 39, 40 and 44, 45. The closing of these contacts completes the circuit of solenoid 33 through wires 37, 38, contacts 39, 40, solenoid 41, wire 43, contacts 44, 45, wire 46, wire 55, switch 56, and wire 57 to the return side of line, this latter circuit being a shunt around resistance 47. The solenoid 33 being energized, the pilot valve is lifted 80 and thereby the direction valve operated as before described to connect the discharge side of the pump directly with the tank 4. After the solenoid core 34 has risen, the switch 56 is opened so that the resistance 47 cuts down 85 the current through the solenoids 33 and 41, this being possible because less current is required to hold the magnet energized than to start it. As the pressure in the tank rises the switch blade 35 of course moves away 90 from the contact 52, but it does not deenergize the magnets as they are self holding through contacts 39, 40 and 44, 45. When however, the switch 35 reaches contact 51, a shunt circuit around magnet 41 is established, comprising wire 50, blade 35 and wire 42, thus deenergizing the solenoid 41 and causing all the circuits to be opened. As the pressure falls the switch blade 35 moves away from contact 51 toward 52 and again 100 establishes a circuit when this latter contact is reached.

The particular description of the motor circuits is not required, though 58 is the motor starting rheostat connected to the main switch 36.

It is thought that from the foregoing description that the nature and advantages of the invention will be fully understood, and it will be seen that I have provided an automatic system wherein the motor and pump may be operated continuously and the load thrown on and off automatically by the pressure in the storage tank.

Various modifications and changes in the specific construction herein described may be made without departing from the scope of the invention.

Having thus described my invention, I declare that what I claim as new and desire to secure by Letters Patent, is—

The combination in a pumping system, with a pressure tank and a low pressure supply, of a continuously operating pump connected between the supply and the pressure tank, a piston operated direction valve connected to permit the pump to discharge into

the low pressure supply or to close such discharge, and means for controlling said direction valve comprising a pilot valve having passages for motor fluid connected to the respective sides of said direction valve for moving it in opposite directions, means for moving said pilot valve in one direction by tank pressure, a solenoid for moving it in the other direction, and a pressure operated switch for controlling said solenoid. 10
In testimony whereof I affix my signature, in presence of two witnesses.
